UNITED STATES PATENT OFFICE

107,144

DESIGN FOR A BADGE OR SIMILAR ARTICLE

Sigmund Stingel, Pittsburgh, Pa.

Application August 11, 1937, Serial No. 71,011

Term of patent 7 years

To all whom it may concern:

Be it known that I, Sigmund Stingel, a citizen of the United States, residing at Pittsburgh, in the county of Allegheny and State of Pennsylvania, have invented a new, original, and ornamental Design for a Badge or Similar Article, of which the following is a specification, reference being had to the accompanying drawing, forming part thereof.

I claim:

The ornamental design for a badge or similar article, as shown.

SIGMUND STINGEL.
